UNITED STATES PATENT OFFICE.

BONIFACE PETRIK, OF ST.-ETIENNE, FRANCE, ASSIGNOR TO SOCIÉTÉ PETRIK & CIE,
OF ST.-ETIENNE, FRANCE.

SPORTING GUN.

Application filed February 20, 1922. Serial No. 538,063.

To all whom it may concern:

Be it known that I, BONIFACE PETRIK, a citizen of France, and a resident of St.-Etienne, Loire, France, have invented certain new and useful Improvements in Sporting Guns; and I do hereby declare the following to be a full, clear, and exact description of the invention, such as will enable others skilled in the art to which it applies to make and use the same, reference being had to the accompanying drawings, and to letters or figures of reference marked thereon, which form a part of this specification.

5 In my application for U. S. patent Serial No. 581,015 a sporting gun is described in which a strap *d* pivots about two axes or trunnions integral with the barrel block and is fitted in grooves provided in the interior 10 wall of the cheeks of the breech piece *g* (Figs. 3 and 7).

As the applicant has proved, the manufacture of the two trunnions or pivots *e*¹ is a somewhat difficult operation, since they are 15 integral with the barrel block and it is necessary that they should be accurately centered.

To remedy this drawback the applicant has devised improvements which form the subject of the present invention, of which 20 the most important consists in making the pivots or trunnions integral with the strap and adapted to enter into holes provided in the cheeks of the break parts of the breech, the sides of the strap engaging in two 25 grooves provided in the side faces of the barrel block. This method permits of the strap being very easily manufactured, since it can be made of two identically similar pieces.

30 The new arrangement practically inverts the position of the male and female organs forming the pivoting connection between the strap, the barrel block and the breech piece.

The accompanying drawings illustrate an 35 example of the improvements according to the invention:

Fig. 1 is an elevation of the rear end of the barrel block of the gun.

Fig. 2 is a vertical section on the line 40 X-X of Fig. 1.

Figs. 3, 4 and 5 are detail views showing the strap, respectively, in front elevation, in side elevation and in plan.

Fig. 6 shows in elevation, partly in section, 45 the strap mounted on the break of the

breech piece, the barrel block being shown in dot and dash lines.

Fig. 6^a is a plan of Fig. 6.

Fig. 7 is a section on the line Y-Y of Fig. 6, the strap not being sectioned so as to 60 show its mounting in the break of the breech piece.

Fig. 8 is a section corresponding to Fig. 7 and showing the gun in the closed position.

Figs 9 and 10 show, respectively, in side 65 view and in plan the cocking piece which is displaced by the strap when the breech piece is opened.

The pivoting connection between the barrel block *C* and the break *g* of the breech 70 piece is obtained by the strap *d*¹ consisting of two absolutely similar pieces which are disposed symmetrically as shown in Fig. 3.

Each piece or half strap *d*¹ carries the pivot or trunnion *c*¹ which is integral with 75 it and which is very easily turned on the lathe. These trunnions or pivots *e*¹ are adapted to engage in holes provided in the sides of the break *g* of the breech piece as shown in Fig. 7. Also, the sides of the 80 strap *d*¹ are fitted in grooves *D* cut on each of the lateral faces of the barrel block as shown in Figs. 1 and 2. These grooves or flats are of sufficient size to allow the strap *d*¹ to engage while taking part in 85 the rotational movement of the barrel block, as shown by the dot and dash lines in Fig. 6.

The displacement of the strap *d*¹ is utilized to cock the gun. For this purpose the piece *E* acting as a cocking piece which is 90 shown in detail in Figs. 9 and 10 has a projection *H* which engages in an aperture *I* of the strap *d*¹ (Figs. 5 and 6). In these conditions when the breech is opened, that is to say when the barrel block is pivoted 95 as shown in the dot and dash lines of Fig. 6, the cocking piece *E* is displaced in the direction of the arrow *F* (Fig. 6) by the strap *d*¹ which determines the cocking.

As shown in Figs. 3 and 5, the strap consists of two similar parts which on the one hand facilitates its manufacture and the other hand allows the strap to be rapidly mounted in the break of the breech piece by the simple engagement of each pivot or 100 trunnion *e*¹ in the corresponding hole of the side *g*.

What I claim is:—

1. A sporting gun comprising a barrel block, a break, side cheeks secured to the 110

break, a removable strap provided between the barrel block and the break, means for securing the said strap to the barrel block, and means for permitting the pivoting of the whole device formed by the strap and the barrel block with reference to the break.

2. A sporting gun comprising a barrel block, a break, side cheeks secured to the break, a removable strap provided between the barrel block and the break, grooves provided in the lateral faces of the barrel block, wherein the sides of the strap are engaged, and means for permitting the pivoting of the whole device formed by the strap and the barrel block with reference to the break.

3. A sporting gun comprising a barrel block, a break, side cheeks secured to the break, a removable strap provided between the barrel block and the break, grooves provided in the lateral faces of the barrel block wherein the sides of the strap are engaged, lateral trunnions secured to the sides of the strap, and holes provided in the internal faces of the cheeks of the break and having the said trunnions engaged therein.

4. A sporting gun comprising a barrel block, a break, side cheeks secured to the block, a removable strap formed in two symmetrical parts provided between the barrel block and the break, grooves provided in the lateral faces of the barrel block wherein the sides of the strap are engaged, lateral trunnions secured to the sides of the strap, and holes provided in the internal faces of the cheeks of the break and having the said trunnions engaged therein.

5. A sporting gun comprising a barrel block, a break, side cheeks secured to the break, a removable strap provided between the barrel block and the break, means for securing the said strap to the barrel block,

and means for permitting the pivoting of the whole device formed by the strap and the barrel block with reference to the break, means for transmitting the displacement of the strap with reference to the break, upon opening the gun, to the mechanism for cocking the gun.

6. A sporting gun comprising a barrel block, a break, side cheeks secured to the break, a removable strap provided between the barrel block and the break, means for securing the said strap to the barrel block, and means for permitting the pivoting of the whole device formed by the strap and the barrel block with reference to the break, means for transmitting the displacement of the strap with reference to the break, a slot provided in the back part of the strap, and a projection engaged therein and secured to the cocking mechanism.

7. A sporting gun comprising a barrel block, a break, side cheeks secured to the break, a removable strap provided between the barrel block and the break, grooves provided in the lateral faces of the barrel block wherein the sides of the strap are engaged, lateral trunnions secured to the sides of the strap, and holes provided in the internal faces of the cheeks of the break and having the said trunnions engaged therein, a slot provided in the back part of the said strap, and a projection provided in the said slot and secured to the mechanism for cocking the guns.

In testimony that I claim the foregoing as my invention, I have signed my name hereto.

BONIFACE PETRIK. [L. S.]
